[57] **CLAIM**

The ornamental design for a film deposit booth, as shown and described.

DESCRIPTION

FIG. 1 is a top perspective view of the film deposit booth showing my new design;

FIG. 2 is an enlarged front elevational view thereof;

FIG. 3 is a reduced scale bottom plan view thereof;

FIG. 4 is a rear elevational view thereof; and

FIG. 5 is a right side elevational view, the left being a mirror image thereof.

The booth shown broken away in FIGS. 2, 4 and 5 is for convenience of illustration.

FIG. 1

FIG. 2

FIG. 3

FIG. 4

FIG. 5
